UNITED STATES PATENT OFFICE.

SCHUYLER C. STEVENS, OF SMITH CENTER, KANSAS.

HEN'S NEST.

No. 857,213.

Specification of Letters Patent.

Patented June 18, 1907.

Application filed March 22, 1907. Serial No. 363,856.

To all whom it may concern:

Be it known that I, SCHUYLER C. STEVENS, a citizen of the United States, residing at Smith Center, in the county of Smith and State of Kansas, have invented a new and useful Hen's Nest, of which the following is a specification.

My present invention relates to improvements in nests for fowls, and it has for its object to provide an improved construction and arrangement of the nests whereby they may be constructed in sections, each section containing a row of nests and the sections being interchangeable and adapted to be assembled according to the size or shape of the hen-house and the number of nests desired, the sectional construction of the nests enabling them to be arranged indoors in superposed arrangement during early setting, and they 20 may be separately placed on the ground outdoors after hatching, the closures or shutters employed in connection with the nests enabling the laying hens to be readily separated from those that are setting.

To these and other ends, the invention comprises the various novel features of construction and arrangement and combination of parts, which will be described more particularly hereinafter, and set forth particularly in the appended claims.

In the accompanying drawing:—Figure 1 is a perspective view of a sectional nest constructed in accordance with the present invention, the nest sections being shown separated. Fig. 2 is a vertical sectional view of the coöperating end portions of the nest sections. Fig. 3 represents a horizontal section through one of the rows of nests in one corner of a hen-house into which the nests are fitted.

Corresponding parts in the several figures are indicated throughout by similar characters of reference.

In the present embodiment of the invention, a pair of upper and lower nest sections A and B are shown, these sections being adapted to interchangeably fit the base section C, it being understood that any suitable number of nest sections may be employed in superposed arrangement, the sections being substantially duplicates in order that they may be built up according to the available space or the number of nests desired.

Each of the nest sections embody in the present instance end pieces 1 and 2 connected by the top board 3, and between these parts

are arranged at suitable intervals a set of partitions 5 which divide the sections longitudinally into a row of separate nests. Extending horizontally across the vertical edges of the end boards and partitions are a pair of strips 6, the upper edge of the strips resting some distance below the upper surface of the top board to provide a space for the interlocking strips of the nest sections, these interlocking strips 8 being secured at the lower 60 sides of each nest section and having their lower edges projecting downwardly beyond the lower edges of the end boards and partitions. The top boards of all the sections, except the uppermost of the set, are provided 70 with a pair of cleats 9 and 10, these cleats being located adjacent the ends of the respective top boards and adapted to engage at the inner sides of the end boards of the section resting thereon.

The base or bottom section is composed of a top board 11 provided with a pair of supporting feet 12 adapted to rest upon the ground or any other suitable means of support, the board 11 being of a width sufficient 80 to fit between the downwardly projecting portions of the lower strips 8 of the lowermost sections, and it is provided with cleats similar to those employed on the nest sections.

The upper and lower horizontal strips 6 and 8 serve as fastening means for the closures or shutters, the latter embodying, in the present instance, a board 14 preferably provided with a ventilation aperture 15 and 90 having a pair of vertically extending cross pieces 16 guided between the adjacent partitions projecting beyond the upper and lower edges of the board, the latter being of a height sufficient to permit a relative vertical 95 movement thereof between the upper and lower strips, the lower ends of the cross pieces projecting a shorter distance beyond the board than the upper ends do in order that they may be disengaged from the lower 100 bars when the closures are lifted, and this permits the closures or shutters to be readily removed and fitted into either side of the nest sections, the weight of the closures serving to prevent accidental displacement, 105 inward movement of the closures being limited by engagement of the cover boards with the vertical edges of the adjacent portions.

In assembling the sections within a hen-

house, the base is so placed on the floor that there will be a space on each side thereof, and on the base are assembled the nest sections, the projecting edges of the lowest strips 8 of 5 the latter engaging the longitudinal edges of the board 11, the latter serving as a bottom for the several nests of the sections and the end boards of the sections fit at the outer sides of the cleats 9 and 10, the latter serving 10 to prevent longitudinal disengagement of the sections while the downwardly projecting portions of the strips 8 coöperate with the longitudinal edges of the board 11 to prevent relative lateral movement or disengagement of 15 the sections. The next section is placed on the lower nest section in a manner similar to that described in the assembling of the base and the lower nest section, the top board of the lower nest section serving as a bottom for the 20 nests in the upper section, the downwardly projecting portion of the lower strips thereon resting immediately above the upper strips 6 on the lower section, the longitudinal edges of the top board coöperating with the lower 25 strips 8 of the upper section to prevent relative lateral disengagement of the sections.

After the sections have been assembled within the hen-house, a suitable partition is erected so as to divide the hen-house into 30 two compartments, the nests being arranged in line with and forming a part of the partition, one side of the nests opening into one compartment while the other side thereof opens into the other compartment. One of 35 these compartments is accessible to the laying hens only while the other compartment is to be occupied exclusively by the setting hens, and the closures or shutters are reversible in order that any desired nest of the series 40 may be placed in communication with either compartment as may be desired.

The superposed arrangement of the nests not only requires very little of the space of the house, but it enables the nest sections to 45 be taken down separately during the hatching season and placed on the ground, and it also provides a construction wherein cleansing may be accomplished very easily, so that the nest may be kept in a sanitary condition, 50 and the shutters or closures may be readily reversed to connect a nest either with the laying or setting compartment, so that the fowls occupying one set of nests cannot interfere with those of the other set. Moreover, 55 the construction is such that the parts are not liable to get out of order, and the nests may be manufactured to sell at a low price, the sectional construction enabling them to be supplied in any desired capacity and to 60 accommodate the nests to the space available in each particular case.

What is claimed is:—

1. A device of the character described composed of coöperatively arranged detachable sections adapted to engage one above 65

the other and having partitions therein dividing them into rows of nests, one of the sections being provided with strips along its lower portion adapted to interlock with the top of the other section to prevent relative lateral disengagement thereof. 70

2. A device of the character described, composed of superposed detachable sections, each section embodying end pieces, a top board connecting them, and horizontally 75 extending strips arranged at the sides thereof, the strips of one section engaging the longitudinal edges of the top board on the adjacent section for preventing relative lateral displacement of the sections. 80

3. A device of the character described composed of superposed detachable sections, each section embodying end pieces, a top board connecting them, partitions arranged transversely of the section and dividing it 85 into a row of nests, strips extending longitudinally of the section and connecting the end pieces and partitions, the lower longitudinal edges of the strips projecting below the lower edges of the end pieces and partitions and 90 adapted to coöperate with the longitudinal edges of the top board of the adjacent section to prevent relative lateral displacement of the sections, and cleats on the upper surface of the top board of one section adapted 95 to engage at the inner sides of the end boards to prevent relative longitudinal displacement of the sections.

4. A device of the character described embodying end pieces, a top board connecting them, partitions arranged transversely of the top board and forming a row of nests, upper and lower parallel strips arranged at each side of the nest, and closures for the nests each embodying a cover board having 100 cross pieces thereon adapted to engage behind the said strips to prevent outward movement of the closures, the ends of the boards of the latter coöperating with the vertical edges of the adjacent partitions to prevent 105 inward movement of the closures. 110

5. A device of the character described embodying superposed detachable sections, each of the latter embodying end pieces, a top board secured thereto, partitions arranged 115 transversely of the section and dividing it into a row of nests, upper and lower horizontal strips arranged on the vertical edges of the partitions and end pieces, the lower pair of strips being arranged to coöperate with the longitudinal edges of the top board of the next lower section to prevent lateral displacement of the sections, and closures for the nests each embodying a cover board adapted to engage the vertical edges of two 120 adjacent partitions and a pair of cross pieces arranged on the rear thereof and adapted to engage the rear sides of the upper and lower strips at either side of the section, the lower ends of the cross pieces projecting a shorter 125 130

distance beyond the lower edge of the cover board than the upper ends project above the upper edge of the cover board, the weight of the cover serving to prevent disengagement of the lower ends of the cross pieces and the lower strip.

5 In testimony that I claim the foregoing as

my own, I have hereto affixed my signature in the presence of two witnesses.

SCHUYLER C. STEVENS.
